SMOKING PIPE ORNAMENT

Regis J. McIntyre, Pittsburgh, Pa.

Application February 2, 1953, Serial No. 23,392

Term of patent 14 years

(Cl. D85—8)

To all whom it may concern:

Be it known that I, Regis J. McIntyre, a citizen of the United States of America, residing in the city of Pittsburgh, county of Allegheny, and Commonwealth of Pennsylvania, have invented a new, original, and ornamental Design for a Smoking Pipe Ornament, of which the following is a specification, reference being had to the accompanying drawing, forming part thereof, wherein:

Fig. 1 is a side elevational view of a smoking pipe ornament, showing my new design;

The broken line showings of a smoking pipe and initials are for illustrative purposes only.

I claim:

The ornamental design for a smoking pipe ornament, substantially as shown and described.
